(57) **CLAIM**

The ornamental design for a dispensing port structure for flexible storage containers for medical use, as shown and described.

DESCRIPTION

FIG. 1 is a perspective view of the dispensing port structure for flexible storage containers for medical use;

FIG. 2 is a front view thereof;

FIG. 3 is a bottom view thereof;

FIG. 4 is a top view thereof; and,

FIG. 5 is a side view thereof, the opposite side view being the same.

The flanges shown in broken lines in FIGS. 1 through 5, and the internal ribs and the internal surface shown in broken lines in FIG. 4 form no part of the claimed design.

1 Claim, 3 Drawing Sheets

FIG. 1

FIG. 2

FIG. 3**FIG. 4****FIG. 5**
